UNITED STATES PATENT OFFICE.

DAVID GRANT, OF CHICAGO, ILLINOIS.

ARCH SUPPORT.

Application filed November 14, 1921. Serial No. 515,050.

To all whom it may concern:

Be it known that I, DAVID GRANT, a citizen of the United States, residing at Chicago, in the county of Cook and State of Illinois, have invented new and useful Improvements in Arch Supports, of which the following is a specification.

This invention relates to arch supports and an object of the invention is to provide 10 an arch support which is constructed of resilient sheet metal and is designed to fit the foot of a user and to embody the proper degree of flexibility and resiliency to cause it to properly conform to the arch of the foot 15 and to give a spring action in walking, as well as to correct the evil effect of improperly braced or supported arches.

Other objects of the invention will appear in the following detailed description 20 taken in connection with the accompanying drawing wherein:

Fig. 1 is a top plan of the improved arch support.

Fig. 2 is a longitudinal section on the line 25 2-2 of Fig. 1 showing the arch support in its normal position.

Fig. 3 is a section similar to Fig. 2, showing the arch support under pressure.

Fig. 4 is a plan of the resilient spring 30 plate.

Fig. 5 is a side elevation of the resilient spring plate, showing the position it assumes when weight is applied thereto, in dotted lines.

Fig. 6 is a detail section taken on the line 35 6-6 of Fig. 1.

Referring more particularly to the drawings, illustrating one of the many constructions of the improved arch plate, the numerations 40 al 1 indicates the base plate which is constructed of suitable sheet metal and is shaped to conform to the interior of a shoe. The base plate 1 is provided with spaced slots 2 and 3 which extend at an angle to each other 45 and open into the recesses 4 formed beneath the base plate by means of the clips or retaining members 5. The members 5 are riveted or otherwise suitably attached to the base plate 1, as clearly shown at 6 in Figs. 2 and 3 of the drawings. The retaining members 5 are provided with substantially semi-circular extensions 5' on their forward edges which fit into substantially semicircular recesses 5a in the tongues 7 and 8 to permit a limited rocking movement of the 55 spring plate 9. The openings or slots 2 and

3 are provided for receiving therethrough the tongues 7 and 8 which are formed upon the resilient spring plate 9. The plate 9 is formed of suitable spring metal and the 60 tongues 7 and 8 project from its side edges directly opposite each other as clearly shown in Fig. 4 of the drawings, while the plate 9 is provided with slots or recesses 10 extending 65 into the tongue 7 and 8 providing relatively short tongues or free edge portions 11 which lie flat against the upper surfaces of the base plate 1 outwardly of the openings 2 and 3 as clearly shown in Fig. 6 of the drawings forming a 70 further support for the spring plate 9.

As clearly shown in Figs. 2, 3 and 6 of the drawings, the upper surfaces of the tongues 7 and 8 abut against the undersurface of the plate 1 providing relatively great 75 bearing surface between the tongues and base plate and permitting yielding resilient movement of the plate 9 as well as permitting limited oscillatory movement of the plate, which various movements are provided to accommodate movements of the 80 foot during walking. The spring plate 9 is arched to conform to the arch of the foot of the wearer and its curved sides 12 and 15 curve upwardly as clearly shown in Fig. 5 85 of the drawings to engage the arch and brace it laterally thereby providing an effective support for the arch of the foot of the wearer, which will yield under pressure into the positions shown in Fig. 3 of the drawings 90 and in dotted lines in Fig. 5 maintaining support for the arch at all times and distributing the weight of the body of the wearer from the arch upon the ball of the foot and heel of the wearer. While in the 95 drawings both side edges of the spring plate or arch 9 are shown curved, it is to be understood that only one side edge may be provided with a curved portion 12 or 15 as desired without departing from the spirit of 100 this invention. The metal plates 1 and 9 of the arch support may be covered by top and bottom layers 13 and 14 respectively, of leather or analogous material. As shown in the drawings, the bottom layer 14 is substantially of the same thickness as the members 5 and is provided with cut out portions 105 which receive the members. It is to be understood that the top cover 13 is removable or may be raised to permit substitution of 110 one resilient spring plate 9 for another.

It is, of course, to be understood that the

invention may be constructed in other manners and the parts associated in other relations and, therefore, I do not desire to be limited in any manner except as set forth in the claim hereunto appended.

Having thus described my invention what I claim is:

An arch support comprising a base plate having spaced slots, a resilient spring plate 10 having tongues on its end edges and provided with recesses extending into the spring plate at each side of said tongues, said tongues being adapted to be inserted through

said slots to separably connect the resilient spring plate to the base plate, said recesses 15 forming relatively short tongues at each side of said first named tongues which engage against the upper surfaces of the base plate when said first named tongues are inserted through said openings, and pocket 20 forming members attached to said base plate and forming pockets for receiving said first named tongues.

In testimony whereof I affix my signature.

DAVID GRANT.
